UNITED STATES PATENT OFFICE.

LOUIS PRESTON MCCHESEY, OF EL PASO, TEXAS.

BOILER.

1,366,268.

Specification of Letters Patent. Patented Jan. 18, 1921.

Application filed May 29, 1919. Serial No. 300,505.

To all whom it may concern:

Be it known that I, LOUIS PRESTON MCCHESEY, citizen of the United States, residing at El Paso, in the county of El Paso 5 and State of Texas, have invented certain new and useful Improvements in Boilers, of which the following is a specification.

This invention relates to an improved boiler particularly designed for domestic 10 purposes and has as one of its principal objects to provide a boiler which may be interposed in the circulating system of a heating plant for heating the water contained within the boiler from the heating 15 fluid of the plant, thereby eliminating the use of the ordinary troublesome water back or heating coil.

The invention has as a further object to provide a boiler which will furnish more 20 hot water than the ordinary boiler employing a water back or coil, other conditions being equal.

A still further object of the invention is to provide a boiler employing a jacket 25 which, under ordinary conditions, will serve as a heating jacket but which, in the summer time, may be drained to provide an insulating jacket adapted to effectually minimize radiation of heat from the water within 30 the boiler as well as prevent the heating of the room in which the boiler is located.

And a further object of the invention in this connection, is to provide a boiler wherein the heating jacket of the boiler will, in 35 the winter time, serve the double purpose of heating the water within the boiler and also heating the room in which the boiler is located.

The figure of the drawing is a vertical 40 sectional view illustrating a boiler embodying my invention.

Referring to the figure of the drawing, I employ a boiler shell 44 and closing the shell at its ends are heads 45 and 46 respectively. Surrounding the shell is a jacket 47 provided at one end with a fixed head 48. Secured within the jacket at its opposite end is an angle plate 49 and rested upon this plate is a removable head 50 for the jacket. 50 This head may be secured to the plate by a plurality of machine bolts or other suitable fastening devices and preferably a gasket is interposed between the plate and head to provide a sealed joint. The head 45 of the 55 boiler shell 44 is provided with couplings

51 into which are threaded pipe sections 52 extending freely through the head 50. Threaded upon these pipe sections to confront opposite side faces of the head 50 are nuts 53 seating against gaskets interposed 60 between the nuts and the head to provide sealed joints between the head and pipe sections. The head 46 of the boiler shell is equipped with a coupling 54 into which is threaded a pipe section 55 extending freely 65 through the fixed head 48 of the jacket. Threaded upon this pipe section to confront opposite side faces of the head 48 are nuts 56 seating against suitable gaskets providing sealed joints between the pipe section and 70 the head. As will thus be seen, the jacket 47 may, when the head 50 thereof is removed, be slipped over the boiler shell 44 when the head 50 may then be placed in position and the nuts 53 and 56 applied 75 upon the pipe sections 52 and 55 and adjusted for positioning the jacket with respect to the shell. This construction, therefore, provides an arrangement whereby boilers already in use may be equipped with a heating jacket. The pipe sections 52 and 55 provide, of course, a means for admitting water to or withdrawing water from the shell. Adjacent one end the jacket is equipped with couplings 57 while similar 80 couplings 58 are arranged adjacent the opposite end of the jacket. These couplings are adapted, as will be well understood, to receive circulating pipes according to the type of heating system in connection with 85 which the boiler is used and, as will be clear, the boiler may be interposed in the circulating system of either a hot water plant or steam plant so that the jacket will, in the first instance, be constantly filled with hot 90 water and, in the latter instance, constantly filled with steam. Thus, the heating medium will be allowed to spread over substantially the entire area of the shell so that the water contained within the shell will 100 accordingly be effectually heated. The jacket is also equipped with an air valve coupling 59 and with a drain coupling 60. As will thus be perceived, the jacket may, in the summer time, be emptied so that 105 when an ordinary burner is employed in connection with the boiler, the jacket will provide a heat insulating jacket for the shell tending to retain the water within the shell hot as well as minimize radiation of 110

heat from the boiler into the room in which the boiler is located. The highly desirable advantages of this feature will at once be appreciated. Further, it will be seen that, 5 in the winter time, the boiler will, since the heating medium will constantly flow through the jacket of the boiler, act to materially heat the room in which the boiler is located.

10 Having thus described the invention, what is claimed as new is:

1. A boiler including a shell, a jacket surrounding the shell, a removable head closing the jacket at one end whereby the jacket 15 may be withdrawn from around the shell, adjustable spacing means between the jacket

and shell, and means for introducing a heating medium into the jacket.

2. A boiler including a shell, a jacket surrounding the shell, coupling means between the jacket and shell whereby the jacket may be adjustably positioned with respect to the shell, and means for introducing a heating medium into the jacket. 20

3. A boiler including a shell, a jacket surrounding the shell, means for adjusting the jacket with respect to the shell, and means for introducing a heating medium into the jacket. 25

In testimony whereof I affix my signature. 30

LOUIS PRESTON McCHESNEY. [L. S.]
